VAPOR DISCHARGE PLUG FOR LIQUID FUEL
BURNERS

Alexander J. Turpin, Stewart Manor, N. Y., assignor to Hauck Manufacturing Company, Brooklyn, N. Y., a corporation of New York

Application February 1, 1946, Serial No. 644,947

1 Claim. (Cl. 299—107)

1 The invention relates to burner apparatus designed for the combustion of liquid fuels such as kerosene and gasoline, and more especially of the vaporizable type of apparatus including preheating means comprising a coiled supply pipe or worm into which a vapor plug or nozzle element is adapted to discharge.

In the use of this type of burner apparatus, it has been found that the plug element quickly becomes clogged with carbon deposits and impurities resulting from vaporizing and cracking of the fuel, and thus requires frequent cleaning of the plug orifice with consequent interruption of the burning operation being conducted with the apparatus. Provision has been made, such as an interposed screen of mesh finer than the orifice opening, to intercept the particles of a size which would not pass said orifice opening. This, however, not only retards the free flow of vaporized fuel but there is built up a deposit on the upstream side of the surface of the screen which, also, is very difficult to remove.

It is an object of the present invention to provide a vapor discharge plug of the aforesaid nature which may be operated for a much longer period in that the required time for cleaning is greatly prolonged.

A further object of the invention is to provide a simple accessory for use with the standard plug, or a special form of plug, whereby particles of matter will be collected as well as diverted in advance of the orifice zone.

In carrying out the invention, there is seated within the hollow cylindrical body of a plug a hollow, frusto-conical guard element which is displaced axially backward, for example, from an inwardly directed wall or outlet end of the plug and in which the orifice is provided, the same being coaxial with the conical element. The latter is provided, also, with a hollow cylindrical tip located in the axis of said orifice and conical element.

By this expedient, particles not intercepted by the conical guard element must pass through its extension before reaching the entrance of the orifice of the plug which is of a much smaller diameter. Particles too large to pass through said orifice instead of accumulating about its entrance will either fall back into the hollow conical element or will collect about the conical inturned wall portion. Particles that do obstruct the opening can be readily displaced to one side of the orifice by inserting from the discharge side a wire cleaning-needle until the collecting space is completely filled. No cleaning will, therefore, be

required until the accumulation becomes such that it will rise to a location directly in front of the orifice. This, however, will be considerably delayed because of the ample storage space provided. Furthermore, the actual cleaning operation is a very simple one requiring merely withdrawing the plug and scraping with a suitable implement such as a nail or wire and then shaking to dislodge the loosened particles.

10 The nature of the invention, however, will best be understood when described in connection with the accompanying drawings, in which:

Fig. 1 is a longitudinal section through the novel vapor discharge plug and a portion of the connecting fuel supply pipe; and Fig. 2 is a similar view illustrating a modification, with supply pipe removed.

Fig. 3 illustrates in longitudinal section a further embodiment of the invention.

20 Referring to the drawings, 10 designates the body of the novel vapor discharge plug, the same being generally cylindrical and threaded at its inner end, as indicated at 11, to be fitted into the end of a fuel supply pipe 12, preferably turned at 90° at the connection to decrease the accumulation of carbon and other particles in the region immediately behind the orifice 13 of the plug. This orifice is located in the longitudinal axis of the cylindrical body 10, being provided through 30 a wall 14 closing the outlet end of the body.

The wall is intended, also, to afford a flange 15 for use in inserting the plug into the supply pipe and disconnecting it therefrom. Furthermore, it is preferred to direct a portion of the 35 wall 14 inwardly symmetrically about orifice 13 which continues through the inwardly directed portion to afford continuous communication between the interior of the body and the said orifice. The inwardly directed portion 16 is of

40 frusto-conical conformation with apex directed toward the inlet end of the plug to afford thereby an annular cavity 17 for receiving and storing particles as they accumulate in the operation of the plug in burner apparatus. However, as indicated in Fig. 2 of the drawings, the body portion 20 of the plug may have this storage portion 21 provided by a reversely directed frusto-conical portion 22.

45 In addition to this provision for storing particles as they accumulate within the body of the plug, a means is provided for preventing the entrance of a substantial proportion of the foreign matter to the region immediately in advance of the orifice entrance. To this end, there is seated in the body 10, Fig. 1, as upon a shoulder 25 thereof, a

hollow, frusto-conical guard member 26, the base of the same resting upon said shoulder for displacing the guard member also a substantial distance in advance of the orifice entrance. The said guard member 26 extends, preferably, beyond the inlet opening 27 of the body, more especially in a tubular extension portion 28 of a diameter appreciably greater than that of the orifice 13. By this expedient, many of the particles are intercepted due to the reduced entrance area and collect in an additional annular pocket or storage space 29 formed between the outer surface of the guard member and the juxtaposed inner surface of the body 10.

It is preferred, also, as where the fuel supply connection to the plug is an elbow such as the elbow 30, to continue the tubular extension 31 of the guard member 32 into the said elbow and to follow its curvature, as is indicated in Fig. 3 of the drawings, thereby increasing the storage capacity for objectionable particles.

I claim:

A vapor discharge plug for liquid fuel burner apparatus, comprising a hollow cylindrical body affording an inner coaxial shoulder and con-

stricted at the outlet end which is provided with an axially disposed orifice, the opposite end of the body being adapted to receive a fuel supply pipe, and an open-ended frusto-conical hollow guard member located within the body on said shoulder coaxially with respect to its orifice and displaced a substantial distance from the orifice entrance, the base of said guard member facing the orifice whereby an annular pocket is provided in advance of the orifice for collection of foreign matter diverted thereto by said guard member.

ALEXANDER J. TURPIN.
